(57) **CLAIM**

We claim the ornamental design for an end counter display unit, as shown and described.

DESCRIPTION

FIG. 1 is a front right perspective view of an end counter display unit showing our new design;

FIG. 2 is a front left perspective view thereof;

FIG. 3 is a left side elevational view thereof;

FIG. 4 is a front elevational view thereof;

FIG. 5 is a back elevational view thereof;

FIG. 6 is a right side elevational view thereof;

FIG. 7 is a top plan view thereof; and,

FIG. 8 is a bottom plan view thereof.

The broken lines in the drawings are for illustrative purposes only and form no part of the claimed design.
